UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL FIXTURE-SUPPORTING DEVICE.

Application filed July 5, 1921; Serial No. 482,473. Renewed April 4, 1924.

To all whom it may concern:

Be it known that I, REUBEN B. BENJAMIN, a citizen of the United States, residing at Chicago, in the county of Cook and State of Illinois, have invented new and useful Improvements in Electrical Fixture-Supporting Devices, of which the following is a full, clear, concise, and exact description; reference being had to the accompanying drawings, forming a part of this specification.

My invention relates to electrical fixture supporting devices and connections therefor.

One of the objects of my invention is to provide an improved fixture supporting device in which the fixture can be readily connected and disconnected with respect to the receptacle, both electrically and mechanically.

A further object of my invention is to provide a thief-proof construction having means for preventing the removal of the fixture by an unauthorized person.

A further object of my invention is to provide such a device which will be simple in construction, cheap to manufacture and durable and efficient in use.

Further objects will appear from the detailed description to follow and from the appended claims.

In the drawings in which an embodiment of my invention is shown—

Fig. 1 is a vertical axial section showing a receptacle, a fixture, and a connecting bracket and plug.

Fig. 2 is a front view showing the receptacle and face plate;

Fig. 3 is a front view of the supporting bracket;

Fig. 4 is a rear view of the bracket and plug-in device; and

Fig. 5 is a perspective view showing a retaining pin.

The construction shown in the drawings comprises a fixture 11, a receptacle 12, a plug-in device 13 for electrically connecting the fixture with the receptacle, and a mechanical connecting member or bracket 14 for mechanically connecting the fixture with respect to the receptacle.

The plug-in device 13 is carried by the connecting bracket 14, being bodily slidably mounted thereon to permit the necessary movement of the connecting bracket 14 to make the mechanical connection without interfering with the insertion of the contact blades 15 of the plug-in device 13 into the

openings 16 provided in the receptacle 12. The mechanical connector member or bracket 14 is secured to the supporting plate 17 (which may be a sort of cover for the outlet box) by means of a pair of hook members 18 at the upper end of the bracket, and a T-shaped headed member 19 at the lower end of the bracket. The supporting plate 17 is provided with a pair of slots 20, to receive the hook members 18, and with a notch 21 adjacent the lower end of the receptacle to receive the headed member 19. The connection of the bracket 14 with the supporting plate 17 is effected by two movements, first a movement of insertion, to bring the hook members 18 and headed member 19 back of the plate 17, and second, a downward movement to engage the hook members 18 and headed member 19 with the supporting plate 17. The sliding movement between the plug-in device 13 and the connecting bracket 14, hereinbefore referred to, permits the downward movement of the connecting bracket 14 without interference from the engagement of the blades 15 in the openings 16.

The sliding connection of the plug-in device 13 with the connecting bracket 14 is effected by means of a pair of lugs 22 struck up from the material of the bracket 14, and the plug being held between the body portion of the bracket and these lugs. The bracket 14 may be a sheet metal stamping, the hook members 18, the headed member 19 and the lugs 22 being formed as integral parts of this stamping.

In order to positively hold the bracket 14 in connected position on the plate 17, a latch pin 23 is provided, which slips in under the insulating base 24 of the plug-in device 13 when the bracket 14 is moved down into connected position with respect to the plate 17, as shown in Fig. 1. In order to cause this latch pin 23 to snap into latching position, a leaf-spring 26 is provided having a forked end portion which bears on the collar 27 on the latch pin 23, to urge the latch pin inwardly to cause it to snap in underneath the insulating base 24 when the bracket 14 is moved downwardly.

In order to prevent theft, or the removal of the fixture by anyone except an authorized person, the construction is such that the latch pin 23 can be released only by use of a special key 28. This key 28 is

insertable through an opening 29 in the canopy 30 and is provided at its inner end with a left-hand screw-threaded socket 31, which screws onto the left-hand threaded shank portion 33 of the latch pin 23. When the key 28 is inserted through the opening 29 and screwed onto the end of the latch pin 23, the latch pin can be released simply by pulling the key 28 outwardly to the dotted line position shown in Fig. 1, thus moving the latch pin 23 out from underneath the insulating base 24, and permitting the bracket 14 to be moved upwardly to release it from engagement with the plate 17. In order to prevent the latch pin 23 from turning when the key 28 is being screwed on or unscrewed, the latch pin 23 is provided with upper and lower flat faces 34, and the opening 35 in the bracket 14 is correspondingly flattened at the top and bottom, so that the pin 23 cannot rotate in this opening. In order to prevent the pin 23 from being drawn out too far, a stop lug 36 is struck up from the material of the bracket 14, this stop lug 36 being located in position to be engaged by the leaf-spring 26 when the pin 23 is pulled outwardly, to limit the outward movement of the leaf-spring, and thus also limit the outward movement of the latch pin 23.

For securing the fixture 11 to the bracket 14, a pair of transversely extending straps 37 are provided, the ends of which are secured to the canopy 30, and the intermediate portions of which are secured to lugs 38, formed integral with the bracket 14, by means of screws 39.

A suitable finishing plate or escutcheon 40 may be provided in front of the supporting plate 17, and secured thereto by means of screws 41.

Having thus described my invention what I claim as new and desire to secure by Letters Patent of the United States is:

1. The combination with a fixture and a receptacle, of means for electrically and mechanically connecting said fixture with respect to said receptacle, comprising a bracket and a plug-in device slidably mounted thereon, said bracket being provided with means whereby it may be connected with respect to said receptacle by

movement toward said receptacle and laterally with respect thereto, means acting between said bracket and plug for retaining said bracket in connected position, and means for preventing the release of said retaining means by an unauthorized person. 55

2. The combination with a fixture and a receptacle, of means for electrically and mechanically connecting said fixture with respect to said receptacle comprising a bracket and a plug-in device slidably mounted thereon, said bracket being provided with means whereby it may be connected with respect to said receptacle by movement toward said receptacle and laterally with respect thereto, means acting between said bracket and plug for retaining said bracket in connected position, and means for preventing the release of said retaining means by an unauthorized person, 60 said means for retaining comprising a pin 65 slidably mounted on the bracket and engaging the plug-in device. 70

3. The combination with a fixture and a receptacle, of means for electrically and mechanically connecting said fixture with respect to said receptacle, comprising a bracket and a plug-in device slidably 80 mounted thereon, said bracket being provided with means whereby it may be connected in position with respect to said receptacle by movement toward said receptacle and laterally with respect thereto, 85 means acting between said bracket and plug-in device for retaining said bracket in connected position, and key-controlled means for releasing said retaining means. 90

4. The combination with a fixture and a receptacle, of means for electrically and mechanically connecting said fixture with respect to said receptacle, comprising a bracket and a plug-in device slidably 95 mounted thereon, said bracket being provided with means whereby it may be connected with respect to said receptacle by movement toward said receptacle and laterally with respect thereto, and means for preventing the disconnection of said bracket 100 by an unauthorized person. 100

In witness whereof, I have hereunto subscribed my name.

REUBEN B. BENJAMIN.
